(Cl. D26—13)

To all whom it may concern:

Be it known that we, Ben Eisenberg and Otto B. Schwarz, citizens of the United States of America, residing respectively at Larchmont, in the county of Westchester and New York city, in the county of New York, both in the State of New York, have invented a new, original, and ornamental Design for Foot Pedal Control for Electric Circuits, of which the following is a specification, reference being made to the accompanying drawing, forming part thereof.

Fig. 1 is a side elevational view of a foot pedal control for electric circuits showing my new design;

Fig. 2 is a top plan view of the invention;

Fig. 3 is a bottom plan view of the invention;

Fig. 4 is an end elevational view of the invention viewed from the right of Fig. 1; and

Fig. 5 is an end elevational view of the invention viewed from the left of Fig. 1.

We claim:

The ornamental design for a foot pedal control for electric circuits, as shown.

BEN EISENBERG.
OTTO B. SCHWARZ.
